UNITED STATES PATENT OFFICE.

SAMUEL B. DAVIS, OF CLINTON, INDIANA, ASSIGNOR OF ONE-HALF TO
THOMAS B. MYERS, OF SAME PLACE.

CLOD-FENDER.

SPECIFICATION forming part of Letters Patent No. 427,160, dated May 6, 1890.

Application filed January 25, 1889. Serial No. 297,585. (No model.)

To all whom it may concern:

Be it known that I, SAMUEL B. DAVIS, a citizen of the United States, residing at Clinton, Vermilion county, State of Indiana, have invented and produced a new and useful Clod-Fender Attachment for Double Cultivator-Plows, of which the following is a specification.

My invention relates to improvements in clod-fender for cultivators; and the objects 10 of my improvement are, first, to provide for the throwing of the clods and similar matters away from the row of corn; second, to prevent dirt from falling directly down on the row of corn; third, to provide for the 15 throwing of loose and fine dirt next to the row of corn from either side; fourth, to provide an arched fender that shall preserve its proper working shape or adjustment, except under great and unusual pressure. I attain 20 these objects by the mechanism illustrated in the accompanying drawings, in which—

Figure 1 is a plan view, and Fig. 2 is an end sectional view.

The letters *a a* represent the runners of the fender, 25 which is composed of two hinged sections. Each of the runners is a solid piece of work, to which the ribs or wires *b b* and the top pieces *c c* are attached by means of rivets.

The letters *d d* represent the hinges fast-

ening the two halves together. This fastening is such that the fender would spread apart flat if it were not for a stop or the position and form of the hinges.

Letters *g g* represent the hind end of the rods *b b* and the top pieces *c c*, so turned as 35 to throw all trash and clods away from the row.

Letters *h h* represent short pieces fastened to the runners by rivets, and having a hole in the front end, into which the middle fore arms *i i* hook. This middle piece is a rod and 40 hooks at the other end into the front piece *g' g'*. The pieces marked *g' g'* fasten to the plow-beams by a bolt.

What I claim as my invention, and desire 45 to secure by Letters Patent, is—

A clod-fender having two sections centrally hinged to each other, each section composed of the runners *a*, the arched ribs or supports *b'*, the rods *b*, and the top central plates *c*, the plates, rods, and runners being turned upwardly and outwardly at their rear ends, the 50 hinges allowing the sections free motion inward, and having a stop to limit their spread substantially as described.

SAMUEL B. DAVIS.
